JAMES HENRY GRESSITT AND HENRY W. FOX, OF BALTIMORE, MARYLAND,
ASSIGNORS TO THE THOMPSON MANUFACTURING COMPANY OF BALTI-
MORE CITY, OF MARYLAND.

HAND-STAMP.

SPECIFICATION forming part of Letters Patent No. 551,928, dated December 24, 1895.

Application filed April 8, 1895. Serial No. 544,920. (No model.)

To all whom it may concern:

Be it known that we, JAMES HENRY GRESSITT and HENRY W. FOX, citizens of the United States, residing at Baltimore, in the 5 State of Maryland, have invented certain new and useful Improvements in Hand-Stamps, of which the following is a specification.

Our invention relates to improvements in hand-stamps of that class which employ an 10 oscillatory impression-block.

The invention will first be described, and then designated in the claims.

In the accompanying drawings, Figure 1 is a side elevation of the stamp. Fig. 2 is a 15 top view of same, except that the depressing-knob is omitted. Fig. 3 is a detail showing the construction of ink-roller bearing. Fig. 4 is a section of the oscillatory block and attached parts. Fig. 5 is a view of the tumble- 20 plate. Fig. 6 is a view of the knob carried on the shaft of the oscillatory block.

The letter A designates two vertical side plates secured together by cross-rods d. A frame or yoke C has one end c pivoted at E 25 between the two side plates, and a torsional spring e wound around the pivot-rod E serves to elevate the free end of the said frame or yoke. The two side plates A have curved front ends f, the said curves forming part of 30 a circle which is concentric with the pivot E. The curved end of one plate has a lug a, which coacts with a notch w on a tumble-plate H, and causes the impression-block B to oscillate or partly turn. The free end of 35 the pivoted frame C has two yoke-arms b and the oscillatory impression-block B, has position between these arms and is carried thereby. A shaft m passes through this block to which it is rigidly fixed, and the shaft ends 40 are free to turn in said two yoke-arms b. The oscillatory block has at one end a recess i, and a spiral spring j is around the shaft and occupies the recess. One end of the spiral spring bears against the inner side of one of 45 the yoke-arms b. Thus this spring serves to push the shaft m and the oscillatory block B endwise and keep them normally pressed over toward the yoke-arm on the other side.

The tumble-plate H, heretofore mentioned, 50 is loose on the shaft m. This plate has two

edges n, substantially at right angles with respect to each other, and the notch w is in the corner adjoining the said two edges. Opposite this notch the tumble-plate has a curved edge o, which extends from one edge n to 55 the other. This plate has a center hole m' for the shaft m, and a series of small holes p around or concentric with said shaft-hole. On the end of the shaft m is a knob q, fixed rigidly, whereby on grasping the knob the 60 impression-block B may be turned. This knob has a short pin p' which will fit in either one of the series of concentric holes p on the tumble-plate.

The block B has a plural number of impression-faces T, whereon a type-plate of rubber may be secured. In the present instance this block has six faces and therefore provides for carrying six different type-plates or impression-plates. The number of concentric 70 holes p in the tumble-plate should correspond with the number of impression or type faces on the oscillatory block, which, as stated, is in the present instance six. From this description it will be seen that the knob q may 75 be grasped and pulled so as to compress the spiral spring j and thereby slide the block B and shaft m endwise and release the pin p' from the hole p it may be in, and thus allow the block B to be turned so as to present a 80 different impression-face for use. Then the said pin p' may be set into another hole p, so as to retain the desired impression-face in the proper relation for printing.

It is desirable to prevent the tumble-plate 85 H from being drawn away from the yoke-arm b when the knob q is pulled, as just described. In other words, when the knob q is pulled it is desirable that the shaft m shall draw freely through both the yoke-arm b and the tumble- 90 plate H, for the reason that only by the tumble-plate remaining stationary can the pin p' on the knob be released or detached from the hole p in the tumble-plate. To insure that this pin will withdraw from the hole it is in, 95 we provide as follows for keeping the plate H stationary when drawing the knob: The yoke-arm b has a groove or slot r and the tumble-plate H has a lateral hook s, which takes in said groove or slot. Thus the plate is coupled 100

or fastened to the yoke-arm without interfering with its freedom of tumbling.

- 5 The side plates A at their highest part and front end have a forwardly-projecting down-curved arm u , provided with a rounded extremity u' , having a bearing v for the journal v' of an ink-roller G. The rounded extremity of each arm u is larger than the ink-roller and has a radial slot or hole x , and a spiral 10 spring y is in this slot or hole and bears against the journal v' . A part-cylindric case z fits on the rounded extremity u' and covers or incloses the ink-roller and also the radial hole x , and confines the spiral spring y therein. 15 15 A screw z' secures the case z on said rounded extremity. By having the down-curved arms u to support the inking-roller, the curved edge o of the tumble-plate H may take up under said curve, as in Fig. 1, and the said arms 20 are not in the way of the knob q . By having the radial slot and spring y , the ink-roller is kept pressed toward the oscillatory block B, and yet said ink-roller may yield or be pushed away by the block B when it passes the roller. 25 25 By having the rounded extremity u' larger than the ink-roller G, the partly-cylindric case z may be fastened on said extremity and cover the ink-roller, and yet leave it free to turn on its journals v' . 30 30 A depressing-knob C' has a shank C², which is secured on the pivoted frame. By pressing down on this knob C' an impression may be made by one of the type-faces T on the oscillatory block B. 35 35 In operation the impression-block B makes at least a quarter turn and back again every time the frame C is depressed, and this is the reason we term it an "oscillatory" block.

Having thus described our invention, what 40 we claim as new, and desire to secure by Letters Patent, is—

1. In a hand stamp, the combination of a pivoted frame having yoke-arms; plate ends having a lug, a ; a shaft revoluble in said yoke-

arms and having slight endwise movement 45 and carrying an impression block; a tumble plate loose on the shaft and having a notch, w , to coact with said lug and a series of holes concentric with the shaft; a knob on the end of the shaft and provided with a pin, p' , to 50 engage one of the holes in the tumble-plate; and means for holding the said loose tumble plate stationary when drawing the shaft endwise so that the shaft may be drawn freely through it in order to detach the knob-pin 55 from one of the holes in the plate, substantially as described.

2. In a hand stamp, the combination of the yoke-arms one of which has a groove, r ; plate ends having a lug, a ; a shaft revoluble in 60 said yoke-arms and having slight endwise movement and carrying an impression block; a tumble plate loose on the shaft and having a notch, w , and a series of holes concentric with the shaft and provided with a lateral 65 hook which engages the groove on the yoke-arm; and a knob on the end of the shaft and provided with a pin, p' , to engage one of the holes on the tumble plate.

3. In a hand stamp, the combination of the 70 side plates, A, provided at their highest part with projecting down-curved arms each having a rounded extremity, u' , a bearing, v , and a radial hole, x ; an inking roller, G, whose journals are in said bearings; a spiral spring, 75 y , in each radial hole and pressing against the journals; a part cylindric case, z , fitted on the said rounded extremities and confining the springs and covering the ink-roller; a pivoted yoke frame; and an oscillatory impression block carried by said yoke-frame.

In testimony whereof we affix our signatures in the presence of two witnesses.

JAMES HENRY GRESSITT.
HENRY W. FOX.
